CLOSING DEVICE FOR RECEPTACLES

Auguste Guiot, Neuilly-sur-Seine, France

Application May 26, 1930, Serial No. 455,825
In France June 1, 1929

1 Claim. (Cl. 210—165)

My invention relates to closing systems for sediment traps for fuel feed conduits provided with a lid which allows of rapidly locking the lid in a fluid tight manner upon a container.

5 With this object in view my invention consists in the combined use of a swinging strap or yoke and of a lever operating as a cam secured upon said strap, the latter bearing upon the container or the lid, and the lever clamping the opposite part.

10 A second characteristic of this invention is that the eccentric boss on the lever applies its clamping pressure in the bottom of a middle semi-spherical cup, so that said boss centers itself correctly in such a manner that the pressure is equally distributed upon the periphery of the contacting surface of the container and of the lid, thus allowing of producing a strictly fluid-tight joint.

15 Owing to its particular arrangement the present device may constitute appropriate means for securing a movable container relatively to a supporting frame acting as lid, and it will be eminently suitable in this respect for securing the body of motor spirit filters upon motor vehicles and for other similar applications.

20 The oscillating strap may be fastened in a stationary or movable manner to a block adapted to seat in a recess in bottom of the container.

25 The appended drawing shows by way of example a mode of construction of my invention in which said strap is pivotally fastened to a block engaging in a recess in the container.

30 The figure is a sectional view of a practical mode of construction applied to a motor spirit filter.

35 In the mode of execution shown in the appended drawing, the device comprises a strap or yoke 1 of steel wire for instance, which surrounds the container R and is provided with two bent portions 1^a which engage holes 2 provided in a block 6 located in a recess in the bottom of the container thus forming a kind of hinges at these points.

40 The strap 1 passes through a lever 3 pivotally connected with the middle portion of the latter which extends over the receptacle. The lever 3 is provided with an eccentric head or cam 3^a which is sufficiently short at one side near the pivot to allow of separating the part constituted by the lever, strap and block from the element constituted by the receptacle and its lid and of placing it in position upon said element.

45 The head of the lever is rounded at 3^c and engages a semi-spherical cup 5 provided in the plug B of the lid C of the receptacle. As may be clearly seen in the drawing the radius of curvature of the rounded portion 3^c of the lever is less than the radius of curvature of the semi-spherical cup 5, whereby the rounded portion is enabled to readily roll or slip in the recess and will come to the position of least resistance. Owing to this arrangement when the lever is brought from the raised position to that shown in the figure, the strap will swing back but the eccentric will come exactly in the middle of the cup 5 and owing to its eccentricity will strongly press the part 6 and the receptacle against the joint J and the lid. 50 The parts are locked in place in a known manner by the oblique position of the strap.

55 It will easily be seen that the operation may be effected almost instantaneously and that owing to the centering of the eccentric in the middle of the cup, the pressure will be distributed uniformly around the periphery of the receptacle opening thus ensuring an absolutely tight joint.

60 The packing J is made for example of pressed cork, the container or receptacle R of glass and the block 6 of metal.

65 My invention may be utilized for rapidly closing and locking in position all kinds of receptacles and its application to filters has only been used as a preferred example.

70 It will also be understood that the steel wire which has a certain elasticity may be replaced by a rigid strap and that if wanted a spring might be used.

75 What I claim and desire to secure by Letters Patent of the United States is:

In a fluid line filter, a head having an inlet and an outlet passage, and having a central opening communicating with said outlet passage, a receptacle having its upper edge engaging the under side of said head, a plug closing the upper end of the central opening of the head, said plug having a semispherical recess, a yoke encompassing the head and receptacle and pivotally engaging the bottom of the receptacle and having an eccentric spheroid pivoted at its upper portion to engage the recess of the plug, the radius of curvature of the spheroid being less than that of the recess, a lever for operating the spheroid, and a filter suspended from a tube extending downwardly into the receptacle from the central opening of the head.

AUGUSTE GUIOT.
